CLAIM

The ornamental design for a template for deck construction
as shown and described.

DESCRIPTION

FIG. 1 is a perspective view of a template for deck construction.

FIG. 2 is a bottom-side view of the template for deck construction shown in FIG. 1;

FIG. 3 is a top-side view of the template for deck construction shown in FIG. 1;

FIG. 4 is a left-side view of the template for deck construction shown in FIG. 1;

FIG. 5 is a right-side view of the template for deck construction shown in FIG. 1;

FIG. 6 is a front-side view of the template for deck construction show in FIG. 1; and,

FIG. 7 is a back-side view of the template for deck construction show in FIG. 1.

The broken lines shown in the drawings represent unclaimed
portions of the template for deck construction and form no
part of the claimed design.

Some broken lines in the drawings represent grooves that
form no part of the claimed design.

1 Claim, 5 Drawing Sheets
